UNITED STATES PATENT OFFICE.

DAVIS MARINSKY, OF NEW YORK, N. Y.

PROTECTOR FOR THE TREAD MEMBERS OF SHOES.

1,375,101.

Specification of Letters Patent. Patented Apr. 19, 1921.

Application filed July 9, 1920. Serial No. 394,903.

To all whom it may concern:

Be it known that I, DAVIS MARINSKY, a citizen of the United States, and residing at New York, in the county of Bronx and State of New York, have invented certain new and useful Improvements in Protectors for the Tread Members of Shoes, of which the following is a specification, such as will enable those skilled in the art to which it appertains to make and use the same.

This invention relates to means for protecting the tread members of shoes, and particularly to devices of this class one of which is shown and described in U. S. Letters Patent No. 1,343,329 granted to me June 15, 1920, and the object of this invention is to provide a protector or protectors of the class described which are an improvement on that described and claimed in said patent, and which while being particularly designed for use in connection with the toe portion of the sole of a shoe may also be used in connection with the side edge portions of said sole at any point; and a further object being to provide a device or devices of the class specified which are simple in form and construction, comparatively inexpensive and which may be applied by anyone at any time to the tread member of a shoe; and with these and other objects in view the invention consists in a device or devices of the class specified, constructed and operating as herein-after described and claimed.

The invention is fully disclosed in the following specification, of which the accompanying drawing forms a part, in which the separate parts of my improvement are designated by suitable reference characters in each of the views, and in which:

Figure 1 is a bottom plan view of the front part of the sole of the shoe showing different uses of my improved sole protector;

Fig. 2 a partial section on the line 2—2 of Fig. 1;

Fig. 3 a view looking in the direction of the arrow 3 of Fig. 2;

Fig. 4 a plan view of a sheet metal blank from which my improved shoe protector is formed;

Fig. 5 a view similar to Fig. 2 but showing a modified method of using my improved shoe sole protector;

Fig. 6 a view similar to Fig. 2 but showing another modification in the method of using the protector;

Fig. 7 a view similar to Fig. 3 but showing a modification;

Fig. 8 a section on the line 8—8 of Fig. 7;

Fig. 9 a view similar to Figs. 3 and 7 but showing another modification; and,

Fig. 10 a section on the line 10—10 of Fig. 9.

In the drawing forming part of this specification, I have shown at *a* the bottom of the front or toe portion of the sole of a shoe and at *b* I have shown two of my improved protectors and the different methods of using the same.

The protector *b* is formed from a sheet metal blank *b*² shown in Fig. 4, which comprises, in the construction shown, a triangular body portion *b*³ provided at the corners of the base thereof with projecting prongs *b*⁴, and the apex of the triangular body portion *b*³ is provided with a projecting tongue *b*⁵ adapted to be folded on a transverse line *b*⁶, and the apex portion *b*⁷ of the body *b*³ adjacent to the tongue *b*⁵ is adapted to be folded on the line *b*⁸, said parts *b*⁵ and *b*⁷ when so folded forming a hook-shaped member *b*⁹ adapted to engage the extreme toe portion of the shoe sole as shown in Figs. 1, 2, 3, 5 and 6, and also in the modifications shown in Figs. 7 and 8.

The body portion *b*³ of the blank from which my improved shoe protector is made, while being shown of triangular form, may be of any desired shape or construction and any preferred dimensions, the only limitation in this direction being that said body portion of the protector should not be wider than the toe portion of the shoe on which it is used.

In applying the protector to the sole or tread member of a shoe the prongs *b*⁴ are bent inwardly so that they can be driven into the sole tread member as indicated in Figs. 2, 5 and 6 and the parts *b*⁵ and *b*⁷ are formed into the hook member *b*⁹, as herein-before described, and in applying the device to the toe portion of the sole of a shoe, the said device is manipulated so as to cause the hook member *b*⁹ to engage and overlap the said toe portion of the sole of the shoe, after which it is driven backwardly so that said hook member will firmly engage said toe portion after which the prongs *b*⁴ are driven into the sole of the shoe.

By constructing the device, as described, and engaging it with the sole of the toe portion of the shoe, or securing it thereto, as

described, the said device will remain firmly and permanently in place without any other really necessary means for securing it, but I may also provide the part b^5 of the hook member b^9 with a prong c which is driven downwardly through the toe portion of the sole as shown in Fig. 5, or I may drive a nail inwardly through the part b^7 of the hook member b^9 as shown at c^2 in Fig. 6, and this will serve as additional means for securing the protector to the sole if such means should be found to be, or be considered necessary. In Fig. 6, I have also shown the body portion b^8 secured in place by nails or 15 tacks c^3 .

In Figs. 7 and 8 I have shown a modification in which a prong d is cut from the material of the part b^7 of the hook member b^9 and driven inwardly into the end of the toe 20 portion of the sole of the shoe as indicated in said figures, and this construction might be used in place of that shown in Figs. 5 and 6 to form supplemental or additional means for securing the protector in position.

The construction shown in Figs. 9 and 10 25 is somewhat similar to that shown in Figs. 7 and 8, except that the part b^7 of the hook member b^9 is cut centrally and diagonally as shown at e to form a plurality of prongs 30 which are driven inwardly as shown in Fig. 10, after the protector has been applied to the shoe sole so that said prongs aid in holding the protector on the shoe sole and also prevent any lateral movement thereof. The 35 prongs shown at d in Figs. 7 and 8 and e in Figs. 9 and 10 are, as will be understood, formed integrally with the hook member and this is also true of the prongs c shown in Fig. 5, and all these prongs as do also the 40 nail or nails c^2 , when the latter are used, prevent any lateral movement of the protector.

My improved protector while being, as hereinbefore stated, designed particularly 45 for use in connection with the toe portion of the sole or tread members of the shoe may, as will be understood, be used in connection with any part of either side edge portion of the sole or tread members for 50 protecting the same at such places; and in Fig. 1 I have shown one of the protectors so applied to one side edge portion of the sole.

The distinctive feature of my improved

shoe protector over other devices of its class 55 is found in the fact that it may be applied to the toe portion of a shoe sole of any shape, whether pointed, rounded or broad, and it may also be applied to the side edge portions of the sole or tread members of a shoe 60 at any point by reason of the shape of and transverse dimensions of the hook member b^9 which engages the sole, and the base or body portion of the protector may be of any desired shape, form and dimensions, and a 65 further distinctive advantage being that when the device is in use it is invisible or approximately so, the hook member b^9 being all that can be seen, and this hook member b^9 may be so formed as to render it almost 70 invisible when the protector is driven firmly into position.

I am fully aware of the fact that many devices of a character similar to mine and for a purpose similar have heretofore been 75 made and used, but no such device having the distinctive features of my protector and the advantages thereof have heretofore been known or used within my knowledge, and while I have shown and described the preferred shape and form of my improved protector and the construction thereof, my invention is not limited to all the details herein set out, and changes therein and modifications thereof may be made, within the scope 80 of the appended claim, without departing 85 from the spirit of my invention or sacrificing its advantages.

Having fully described my invention, what I claim as new and desire to secure by 90 Letters Patent, is:—

A tread protector of the class described composed of a triangular sheet of metal, one of the corner portions of said sheet being provided with a narrow hook-shaped member 95 adapted to engage the edge portion of that part of the tread member to be protected, and means at the other corner portions of said sheet for securing the same to the bottom face of the tread member. 100

In testimony that I claim the foregoing as my invention I have signed my name in presence of the subscribing witnesses this 7th day of July, 1920.

DAVIS MARINSKY.
